GARMENT ATTACHMENT

Hartman K. Harrison, Baltimore, Md.

Application July 13, 1936, Serial No. 90,399

2 Claims. (Cl. 2-87)

This invention relates generally to wearing apparel, and its general object is to provide an attachment that is primarily designed for use with raincoats and the like for disposal circumferentially about the inner side adjacent to the lower edge thereof, to hold the latter spaced outwardly and away from the garments worn below the same, to direct rain water and the like accordingly from the garments as well as from the shoes of the wearer, so as to prevent water damage thereto and discomfort caused by water soaked or wet material.

A further object of the invention is to provide a rain garment attachment of the character set forth that is inflatable, and is filled with air when in use, to accomplish its intended purpose, yet is inconspicuous when inflated or deflated, in that it is hidden from view at all times, and when deflated is flat and lies accordingly against the garment to which it is attached.

Another object of the invention is to provide a rain garment attachment that may be permanently fixed thereto, or detachable therefrom, causes no discomfort, can be readily inflated and deflated, is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view illustrating my attachment applied to a raincoat and in use.

Figure 2 is a sectional view taken approximately on line 2—2 of Figure 1.

Figure 3 is a fragmentary view showing the device or attachment deflated.

Figure 4 is a similar view showing the device inflated.

Figure 5 is a sectional view taken approximately on line 5—5 of Figure 2.

Referring to the drawing in detail, it will be noted that I have illustrated my device as being attached to a raincoat, for use therewith, but I want it understood that it can be attached to any type of rain garment, and in the form as shown includes essentially a relatively narrow strip, preferably made from rubber or other leak proof material in a manner to form a tube portion pro-

viding a chamber 1 of cross sectional rounded or oval configuration, extending longitudinally and centrally of the strip to provide flat upper and lower portions 2 and 3 respectively. The tubular portion is preferably co-extensive with the length 5 of the strip, and has one end closed as at 4, while the opposite end is open, for the purpose of introducing air therein by any well known means, or merely by manually blowing therein, until the tubular portion becomes inflated, as will be apparent.

The open end of the tubular portion is closed merely by folding the strip upon itself as shown in Figure 2 and applying a U-shaped clamp 5 to the folded portions, so as to prevent the escape 15 of air therefrom.

The open end of the tubular portion may be reduced to provide a nipple, but in any event the open end portion is folded upon itself in a manner suggested in Figure 5 and held accordingly by 20 the clamp 5, to prevent the escape of air from the chamber.

The attachment is preferably disposed adjacent to the bottom of the garment, and may be permanently fixed or detachably secured thereto. 25 In any event, it is desirable to have the upper edge of the upper portion 2 fixed to the garment, as best shown in Figures 3 and 4, so that when the device is inflated, the portion of the garment below the upper edge of the upper portion 30 2 will be directed outwardly to a major degree, as best shown in Figure 4, and therefore direct rain water accordingly so as to prevent the latter from contacting garments that extend below the rain garment, or adjacent to the lower edge thereof, 35 as well as the shoes of the wearer, thereby retaining the same in a reasonably dry condition, as will be apparent.

It is thought from the foregoing description that the advantages and novel features of the 40 invention will be readily apparent.

It is to be understood that changes may be made in the construction and in the combination and arrangement of the several parts, provided that such changes fall within the scope of the 45 appended claims.

What I claim is:

1. A garment comprising a freely depending skirt like portion, a strip of elastic material including a flat portion secured circumferentially 50 about the inner side of the skirt like portion adjacent to the lower edge thereof, an inflatable tubular portion included in the strip and having an open end, said tubular portion adapted when inflated to hold said lower edge of the skirt like 55

portion outwardly flared, and means for closing the open end.

2. A garment comprising a freely depending skirt like portion, a strip of elastic material, a tubular portion formed on said strip to provide a chamber extending along the longitudinal center thereof to provide upper and lower flat portions, said upper flat portion being secured to the skirt

like portion circumferentially about the inner side adjacent to the lower edge thereof, and said tubular portion having a closed end and an open end and adapted to be inflated to hold said lower edge of the skirt like portion outwardly flared and means for closing the open end. 5

HARTMAN K. HARRISON.
